(57) **CLAIM**

The ornamental design for an equine pastern wrap, as shown and described.

DESCRIPTION

FIG. 1 is a top, front, right perspective view of an equine pastern wrap, showing our new design fastened and in a first configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top plan view of the equine pastern wrap of FIG. 1, shown with the wrap open and flattened in a second configuration; and,

FIG. 9 is a bottom plan view thereof.

In the drawings, the broken lines on the equine pastern wrap depict stitching and form part of the claimed design. The drawings are shaded to indicate contrasting surfaces.
